E. J. RAUCH.
CAR HEATER.
APPLICATION FILED OCT. 1, 1907.

914,305.

Patented Mar. 2, 1909.

UNITED STATES PATENT OFFICE.

EDGAR J. RAUCH, OF TAUNTON, MASSACHUSETTS.

CAR-HEATER.

No. 914,305.

Specification of Letters' Patent.

Patented March 2, 1908.

Application filed October 1, 1907. Serial No. 395,444.

To all whom it may concern:

Be it known that I, EDGAR J. RAUCH, of Taunton, in the county of Bristol and State of Massachusetts, have invented certain new and useful Improvements in Car-Heaters; and I do hereby declare the following to be a full, clear, and exact description of the invention, such as will enable others skilled in the art to which it appertains to make and use 10 the same.

The object of this invention is to utilize the heat energy heretofore wasted in the metallic resistance of the motor circuit of an electric car to heat water which is caused to circulate 15 through pipes within the car-body for the purpose of heating the car.

A further object is to provide means whereby the current may be directed through resistance coils used for water heating purposes, when desired, or connected to an ordinary air-cooled resistance when it is not desired to use the current for heating, that is, the current may be wholly or in part shunted into either resistance.

25 The invention will be hereinafter fully set forth and particularly pointed out in the claims.

In the accompanying drawings, Figure 1 is a vertical longitudinal sectional view of a 30 car equipped with my improvement. Fig. 2 is a diagrammatic view showing the electric circuits. Fig. 3 is a detail, showing one of the tanks with resistance wires.

Referring to the drawings, 1 designates a 35 car-body, conventionally indicated; 2 water-pipes located therein; 3 an ordinary expansion tank; and 4 a series of metallic vessels or chambers, preferably of iron or steel, located under the floor of the car and lined 40 with porcelain or other non-conducting material, and preferably located within a second tank for retaining the heat. These vessels are connected to pipes 2 by flow and return pipes 5, as in ordinary hot-water systems. 45 Within each of the vessels 4 are rods 6, covered with suitable non-conductors, such as porcelain. These rods support motor-circuit resistance coils 7, connected to the wires from the controlling mechanism by ordinary binding posts.

While I have shown a series of tanks, yet a single tank may be employed if desired.

The motor current being caused to pass through resistance coils within the water-containing vessels, the heat of the coils is taken off by the water, which being heated will circulate through pipes 2 and thereby heat the car. But, when it is not desired to utilize hot water, or the temperature thereof is to be regulated, the motor current may, in 55 whole or in part, be shunted by a switch, or switches, as at 8, into resistance coils 9 which are, as ordinarily, cooled by air circulation. These switches are under the control of the motorman, and the intensity of the heat of 60 the water depends upon the amount of current directed into the submerged coil.

The advantages of my invention are apparent. It will be seen that the heat energy now 70 ordinarily lost through the motor-circuit resistance coils is utilized in whole or in part, for heating water by which electric cars may be heated.

I do not confine myself to any special arrangement, the invention being capable of 75 being carried out by various means.

I claim as my invention:

1. The combination with an electrically propelled car, of a water circulating system therein, a rheostat within the car motor circuit, a water containing receptacle, comprising a part of said system, inclosing said rheostat, a separate air-cooled rheostat, and means for connecting either or both of said 80 rheostats in circuit with the motor.

2. In combination with an electric car having water pipes, tanks from which said pipes lead, motor-circuit resistance coils located within said tanks, a second set of motor-circuit resistance coils located outside of said 90 tanks, and means for diverting the motor current into either or both sets of coils.

In testimony whereof, I have signed this specification in the presence of two subscribing witnesses.

EDGAR J. RAUCH.

Witnesses:

E. H. CAMPBELL,
JAMES M. SWIFT.
